SAFETY DEVICE FOR WINDING AND UNWINDING ROLLERS.

1,412,994.

Specification of Letters Patent. Patented Apr. 18, 1922.

Application filed June 8, 1921. Serial No. 475,942.

To all whom it may concern:

Be it known that I, WARREN E. BEADLE, a citizen of the United States, residing at Grand Rapids, county of Wood, and State of Wisconsin, have invented new and useful Improvements in Safety Devices for Winding and Unwinding Rollers, of which the following is a specification.

This invention relates to improvements in safety devices for winding and unwinding rollers, and has particular reference to devices for preventing accidents in paper mills where a plurality of rollers are interchangeably employed as receiving rollers for the paper strip delivered from the drying rolls.

In a paper mill the newly formed paper winds upon a receiving roller, and in order that the operation may be continuous it is customary to employ two receiving rollers, one above another, whereby when a roll of paper has been formed on one of the rollers to a desired diameter or radial thickness the strip of paper may be torn off and attached to the other roller upon which it then winds. In the meantime the paper is withdrawn from the first mentioned roller and passes to what is known as a rewinding roller which carries suitable spools or cores, and with which slitters are associated to subdivide the strip longitudinally into strips of the desired width for shipment and commercial use.

It is a frequent occurrence that the winding of the paper on one roller and the unwinding it from the other roller do not take place simultaneously or with uniform speed, and therefore the peripheries of the two rolls of paper may at times be in such close proximity as to constitute a source of danger to workmen who might accidentally be drawn between the rolls.

The laws of various States have therefore required attachments for automatically preventing a continuation of a winding operation in any case where the peripheries of the two rolls are less than a specified distance apart, eight inches being usually specified as the minimum distance permissible. But the attachments heretofore have been of a character to limit the possible diameter of a roll without regard to the diameter of the companion roll. This is a serious disadvantage for the reason that such limits must necessarily be predetermined and arbitrarily

fixed upon a calculation based upon the assumption that the accompanying roll is of equal diameter, i. e., at the maximum diameter, whereas the companion roll is more commonly nearly unwound at the time the winding roll reaches the maximum diameter permitted by the gage.

It is the object of this invention to provide a form of gage which may be adjusted between a set of companion winding rolls in a position for contact with the roll which is being augmented, the gage, however, being adapted to yield progressively as the diameter of the roll increases until it is also brought in contact with the companion roll or roller, under which conditions it operates to prevent further delivery of paper to the roll which is being wound.

More particularly it is an object of this invention to provide a yielding gage adapted for contact with a revolving roll of paper without any tendency to tear the paper, and which is also adapted to yield until it engages the companion roll, whereupon it becomes effective to tear the paper strip and prevent further deliveries to the active receiving roller until the condition which caused the operation of the gage has been remedied.

By providing a gage adapted for rolling contact with the paper on the receiving roller and making such gage equal in diameter to the minimum distance permissible between the paper on the receiving roller and that of the companion roller, I have found that it is possible to mount the gage upon a yielding support and allow it to be freely turned by frictional contact with the paper on the receiving roller until its periphery on the opposite side of the axis engages the paper on the companion roll, whereupon its rotary motion is arrested and it becomes effective as a tearing agency, the surfaces of the two rolls, (winding and unwinding) traveling in opposite directions on the side where such contact occurs.

An embodiment of my invention is illustrated in the accompanying drawings, in which—

Figure 1 is a front elevation of my invention as it appears in use, fragments of a set of companion winding rollers being illustrated with rolls of paper thereon.

Figure 2 is a side view of the same.

Like parts are identified by the same reference characters throughout both views.

1 and 2 are companion rollers, such as are employed in paper mills, to receive the strip 5 of paper from the drying rolls. The drawing illustrates the roller 1 in operation as a receiving roller, the paper strip 3 being illustrated as being wound thereon to form the roll 4. The roller 2 is illustrated as it 10 appears when unwinding, the paper strip 5 being drawn from this roller. Therefore, the roll of paper 6 on the roller 2 is diminishing in size, whereas the roll of paper 4 on the roller 1 is augmenting in size.

15 The gage roller 8 is mounted rotatably upon a shaft 9 carried by a supporting member 10. A lever 11 pivotally connected with the supporting member 10 at 12 is fulcrumed at 13 upon a bracket 14 connected with any 20 suitable post or frame member 15 located at one side of the paper making machine adjacent to the receiving rollers 1 and 2. A counter-weight 15 is adjustably mounted upon the lever 11 to balance the weight of 25 the gage roller 8. A link 17 connects the supporting member 10 with the bracket 14. This link is parallel with the lever 11, and the arrangement is such that the shaft 9 is supported in a horizontal position, or in a 30 position parallel with the rollers 1 and 2, and this parallelism will, of course, be maintained by the lever 11 and link 17 while the roller 8 is being moved vertically, inasmuch as the roller supporting arm of the lever 11 35 is of the same length as the link 17.

The counter-weight 15 is preferably adjusted to substantially balance the weight of the roller 8 and associated parts so that the roller 8 will tend to remain in any position 40 of adjustment in which it may be placed, the roller, however, being free to yield under pressure without material resistance.

Therefore, if it be assumed that the lever 45 11 is adjusted in a horizontal position as shown in Figure 1, the paper may be wound freely upon the roller 1 until the roll 4 acquires a diameter equal to that illustrated in Figure 1, at which time the roll 4 contacts with the roller 8 on the lower side.

50 Thereupon, motion is transmitted to the roller 8 by reason of this frictional contact of the roll 4, and as the diameter of the latter increases the roller 8 is pushed downwardly toward the roll 6.

55 Assuming that the roll 6 is stationary, the unwinding operation having been stopped for some reason, the roller 8 will continue to descend until it reaches the dotted line position indicated in Figure 1, the roll 60 4 having augmented sufficiently to force the roller 8 downwardly to this dotted line position.

But as soon as the roller 8 contacts with the roll 6 its rotary motion will be arrested 65 by a friction upon the roll 6, and as soon as

this occurs the corresponding friction upon the periphery of the roll 4 at the point of roller contact will cause the paper to tear. When torn at or near one margin the strip may immediately tear entirely across under 70 the tension of the winding operation, thus preventing any further augmentation in the size of the roll 4.

If the roll 6 should be unwinding at the time the roller 8 is brought in contact with 75 it the same result would be accomplished, for the paper unwinds from the underside of the roller 2, and therefore the roller 2 and roll 6 will revolve in the opposite direction from that in which the roller 1 and 80 roll 4 revolve.

I claim:

1. A safety gage for sets of winding and unwinding rollers comprising a yielding rotative device located between the rollers and 85 adapted to be actuated by a roll wound upon either roller in the contact with the other roller or with a roll thereon, said device being adapted to limit the distance between the rolls by stopping the winding operation 90 when in contact with both.

2. A safety gage for sets of winding and unwinding rollers comprising a gage roller and a support adapted to yieldingly hold the gage roller between the other rollers, said 95 gage roller being adapted to stop a winding operation upon one of the rollers when in contact therewith and in simultaneous contact with the other roller or with a roll of material thereon.

3. The combination with winding and unwinding rollers adapted to serve as receiving rollers for a strip of paper in process of manufacture comprising the gage roller having a diameter substantially equal to the 105 permissible distance between the peripheries of rolls of paper on the other rollers, a pivotal support for the gage roller, and a parallel link adapted to cooperate with the pivotal support in holding the gage roller 110 with its axis parallel to the axes of the other rollers.

4. The combination with a set of receiving rollers for paper strips, of an intermediate gage roller having a diameter substantially equal to the permissible distance between rolls of paper on the receiving rollers, a member upon which said gage roller is journaled, a relatively fixed support, parallel arms pivoted thereto and also 120 pivoted to the roller carrying member and adapted to hold said member with the roller axis parallel to the receiving rollers, and means for counterbalancing the gage roller at associated parts whereby the same will 125 tend to remain in one position until actuated by contact with an augmenting roll of paper on one of the receiving rollers.

5. The combination with a set of receiving rollers for paper strips, of an intermediate 130

gage roller having a diameter substantially equal to the permissible distance between rolls of paper on the receiving rollers, a member upon which said gage roller is journaled, a relatively fixed support, parallel arms pivoted thereto and also pivoted to the roller carrying member and adapted to hold said member with the roller axis parallel to the receiving rollers, and means for counter-balancing the gage roller at associated parts whereby the same will tend to remain in one position until actuated by contact with an augmenting roll of paper on one of the receiving rollers, said gage roller being positioned for contact with the augmenting roll of paper adjacent to one end thereof whereby when the gage roller is brought in con-

tact with the other roller or with a roll of paper thereon, the paper strip winding upon the augmenting roll will be torn away. 20

6. The combination with a receiving roller for winding into roll form a paper strip, a gage roller, parallel motion mechanism for supporting the gage roller between the first mentioned roller, and a relatively fixed member, said gage roller being adapted to rotate in contact with a roll of paper winding upon the first mentioned roller and to yield progressively under such contact until it also engages the relatively fixed member 25 to arrest its rotary motion and cause the paper strip to tear. 30
